United States Patent Office

Des. 202,288
Patented Sept. 14, 1965

202,288

DOOR FOR VENDING MACHINES OR THE LIKE

Harry Greenwald, New York, N.Y., assignor of one-third
each to Louis Wolff and Harry Silberglaib, both of
Brooklyn, N.Y.

Filed Nov. 18, 1964, Ser. No. 82,673

Term of patent 14 years

(Cl. D52—3)

FIG. 1

FIG. 2

FIG. 3

FIG. 4

FIG. 1 is a front elevational view of a door for vending machines or the like, showing my new design;

FIG. 2 is a side elevational view thereof;

FIG. 3 is a rear elevational view thereof; and

FIG. 4 is a top plan view thereof.

I claim:

The ornamental design for a door for vending machines or the like, substantially as shown,
